UNITED STATES PATENT OFFICE.

JAMES P. CARNEY, OF DETROIT, MICHIGAN, ASSIGNOR OF ONE-HALF TO CATHERINE E. LONG, OF CHICAGO, ILLINOIS.

EMERGENCY-KNUCKLE FOR CAR-COUPINGS.

1,379,960.

Specification of Letters Patent. Patented May 31, 1921.

Application filed February 7, 1920. Serial No. 356,841.

To all whom it may concern:

Be it known that I, JAMES P. CARNEY, a citizen of United States, residing at Detroit, in the county of Wayne and State of Michigan, have invented a certain new and useful Improvement in Emergency-Knuckles for Car-Couplings, of which the following is a full, clear, concise, and exact description, reference being had to the accompanying drawings, forming a part of this specification.

This invention relates to improvements in emergency knuckles for car couplers.

As is well known, in the operation of railway cars, the knuckles of the couplers are frequently broken and also the pin-locking devices frequently get out of order, thereby rendering the couplers inoperative. In order to permit of the cars having such broken couplers taken to their destination without setting the car aside, it is necessary to employ some emergency device to effect a temporary coupling between the cars. Heretofore, such emergency devices have included either chains or various types of so-called emergency knuckles. The chains are of course generally wholly inadequate and the emergency knuckles, heretofore used, have not proven satisfactory for the reason that they have involved a pin-locking arm thereon somewhat similar to the regulation knuckle. With emergency knuckles having pin-locking arms, as above indicated, it is necessary to take out certain of the interior parts of the coupler which requires time and the use of tools.

The object of my invention is to provide an emergency knuckle for car couplers which may be very quickly applied to a defective coupler by merely substituting the emergency knuckle for the original knuckle and holding it in place by the same knuckle pin and without the necessity of touching any of the interior parts of the coupler.

Another object of my invention is to provide an emergency knuckle for car couplers which not only will conform to all of the requirements of standardized couplers as regards spacing between coupler heads and ability to effect the interlocking of two couplers without the brakeman entering between the cars but which will also be usable with all of the different commercial types of Master Car Builders' couplers which

vary in certain respects not covered by the standardized rules.

In the drawing forming a part of this specification, Figure 1 is a top plan view of two interlocked couplers of standardized construction, one of which is fitted with a regular knuckle and the other of which is fitted with an emergency knuckle embodying my invention. The coupler having an emergency knuckle has part of the top wall thereof broken away and a portion of the side wall shown in section in order to more clearly illustrate my improvements. Fig. 2 is a top plan diagrammatic view illustrating the co-operative relation between my improved emergency knuckle and parts of several different commercial types of couplers. And Fig. 3 is a side elevational view of the improved knuckle.

In said drawing, each coupler is shown as provided with the usual shank 10 and head 11, the latter having formed integrally therewith the usual guard arm 12. The left-hand coupler, as viewed in Fig. 1, is provided with a regular knuckle 13 pivotally connected to the coupler head in the usual manner by the knuckle pin 14, it being understood that said knuckle 13 is provided with an arm extended within the coupler head which is adapted to be locked in closed position and also released by the locking-pin 15. The right-hand coupler, as viewed in Fig. 1, is provided with my improved emergency knuckle indicated generally by the reference A.

The improved emergency knuckle, as shown, is formed with what may be termed a main arm 16 which, in shape and size, conforms to the standards of the Master Car Builders' Association and which is therefore adapted to interlock with a regular standard knuckle such as that indicated at 13. My improved knuckle A is also provided with a heavy pivot lug 17 of such vertical height that it is adapted to fit between the usual spaced upper and lower walls of a coupler and said pivot lug is centrally perforated as indicated at 18 to receive the knuckle pin 114. So far as the parts of the emergency knuckle have been described, they are the same as a regulation knuckle such as indicated at 13 and therefore adapted to be interchanged with the latter.

On the outer side of the pivot lug 17, that is, on the side substantially diametrically opposed to the said main arm 16, the knuckle A is provided with an outwardly and rearwardly extending rib 19 which is separated from the main body of the pivot lugs 17 as indicated by the recess 20 in Fig. 2. Said rib 19 is provided with a vertically extending, outwardly and rearwardly inclined or beveled face 21 which is adapted to bear against and co-act with the vertically extending forward edge 22 of the usual side wall 23 of a coupler head. As clearly indicated in Fig. 3, the height of the rib 19 is slightly greater than the vertical height of the pivot lug 17, that is, the height of the rib 19 is slightly less than the vertical distance between the usual upper and lower walls of a coupler head.

The regulations of the Master Car Builders' Association, of course, provide for certain standard dimensions and contours on all couplers employed in railway service and all manufacturers of couplers necessarily follow these regulations. There are, however, certain parts of the coupler which may be varied by the manufacturers and whose specific location and form are not strictly within the regulations of the Master Car Builders' Association with the result that, in actual practice, the various commercial types of standardized car couplers vary in certain details. Among these details which are varied by the different manufacturers is the side wall such as indicated at 23 in Fig. 1. There are various commercial types of car couplers on the market which have the side walls of the head and the forward vertically extending edges thereof, on the opposite side of the coupler to that of the guard arm, varied in location with respect to the axis of the knuckle pin as indicated by the four forward edge contours 123, 223, 323 and 423 shown in Fig. 2.

It is in order to take care of the differences in commercial types of car couplers with respect to the side wall and forward edge thereof corresponding to that indicated at 23-22, that I provide the beveled face 21 of my emergency knuckle and this is an important feature of my invention. By forming the beveled face 21 as described and shown, it is evident that my emergency knuckle will always be held in the same place, with respect to the knuckle of an opposing coupler or the guard arm of the same coupler, regardless of the particular commercial type of coupler to which it is applied. In other words, by making the contour of the bearing face 21 of my emergency knuckle conform to the locus of termini of the side walls of the several commercial types of couplers now on the market, I am enabled to maintain my emergency knuckle always in the same relation with the stand-

ardized parts of the coupler and in this way, the railroads need only keep on hand the one type of emergency knuckle such as I have indicated.

From the preceding description, it will be seen that my improved emergency knuckle will be held in one position and cannot be swung outwardly and in an opening direction. The position assumed by the emergency knuckle is that of a "closed" regulation knuckle and hence can be coupled with another coupler having the knuckle thereof in open position without the necessity of the brakeman entering between the cars. Once interlocked and with the regulation knuckle held in locked or closed position by its pin-locking arrangement, the two couplers act as would two uninjured couplers and are therefore enabled to maintain the proper spacing between the couplers and the cars and prevent disconnection of the hose as well as prevent increase of danger of injury to the brakeman while passing from one car to another.

There are some couplers on the market which are formed with upper and lower walls of a contour and depth differing considerably from most other couplers now in service and to adapt my emergency knuckle to said couplers, the emergency knuckle may be recessed or notched on its upper and lower faces as indicated at 24-24, the notches 24 being of such depth as to bring the bottoms thereof flush with the top and bottom surfaces of the pivot lug 17, as will be evident from an inspection of Fig. 3.

I claim:

1. An emergency knuckle for car couplers which conform to standardized requirements and have a wall providing a forward edge extending vertically on the opposite side of the coupler to that of the guard arm, said knuckle having an inwardly extending main arm conforming to standardized requirements, a perforated pivot lug adapted to be inserted between the upper and lower walls of the coupler head and be pivoted thereto by a knuckle pin, and a vertically extending, substantially outwardly and rearwardly facing surface on its outer portion arranged to bear against the said vertically extending edge of the side wall of the coupler head to thereby hold the knuckle against opening movement and in a predetermined position with respect to standardized parts of the coupler, the contour of said outwardly and rearwardly facing surface conforming to the locus of the vertically extending forward edges of the side walls of a plurality of couplers differing in this respect, whereby the emergency knuckle is interchangeably usable with couplers differing as aforesaid.

2. As an article of manufacture, an emergency knuckle for car couplers, said knuckle having a main arm adapted to in-

terlock with the knuckle of a second coupler, a pivot-forming lug, and a rib disposed on the opposite side of the lug to that of said main arm, said rib having a vertically arranged shoulder formed to bear against the forward edge of an adjacent corresponding side wall of the coupler to which the emergency knuckle is adapted to be applied, the contour of said shoulder adapting it to coöperate with different couplers to always maintain the main arm of the knuckle in the same position relatively to the knuckle of the said second coupler.

3. An emergency knuckle for car couplers which conform to standardized requirements and have a side wall providing a vertical forward edge on the opposite side of the coupler to that of the guard arm, said knuckle having an inwardly extending main arm conforming to standardized requirements, a perforated pivot-forming lug of lesser height than said main arm and adapted to fit between the usual upper and lower

walls of the coupler head and be pivotally connected thereto by a knuckle pin, and a vertically extending rib on the opposite side of the pivot-forming lug to that of said main arm, said rib having a substantially rearwardly facing, vertically extending surface, the contour of which conforms to the locus of the vertically extending forward edge termini of the side walls of a plurality of couplers differing in this respect, whereby the emergency knuckle is interchangeably usable with couplers differing as aforesaid so as to insure the inwardly extending main arm of the knuckle always assuming the same relative position with respect to the standardized parts of the coupler to which it is applied.

In witness that I claim the foregoing I have hereunto subscribed my name this 21st day of January, 1920.

JAMES P. CARNEY.

Witness:

META SCHMIDT.
